UNITED STATES PATENT OFFICE

JOSEPH S. BENNETT, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

WATER COOLED STOKER

Application filed October 11, 1929. Serial No. 398,924.

This invention relates to a water-cooled stoker furnace.

An important object of the invention is the provision of a stoker arrangement permitting cooling of the tuyères or of the tuyères and retort walls as desired, thus increasing the life of the various stoker parts affected by the increasing tendency to use of highly pre-heated air therein.

10 A further object of the invention is to provide a construction of this nature which will permit the cooling to be extended to the over-feed section.

15 A still further object of the invention is to provide a construction of this character which, if so desired, may be extended to include the adjacent wall of the crusher pit.

20 A further object of the invention is to provide a structure of this character which may be employed to provide cooling of any or all of these sections.

25 A still further object of the invention is the production of a structure of this character which may be incorporated in a stoker furnace without materially modifying the construction thereof.

30 A further object of the invention is to provide a stoker structure wherein the entire area of the stoker body and furnace walls within the fire zone is water-cooled.

35 A still further and more specific object of the invention is to provide a structure permitting cooling of the pushers and partition plates thereof.

40 These and other objects I attain by the construction shown in the accompanying drawings wherein, for the purpose of illustration, I have shown a preferred embodiment of my invention and wherein:

45 Fig. 1 is a vertical sectional view through a stoker furnace embodying water-cooling of the portions thereof lying within the fire zone and of the crusher pit wall;

Fig. 2 is a section on line 2—2 of Fig. 1;

Fig. 3 is a section on line 3—3 of Fig. 1;

Fig. 4 is a vertical longitudinal sectional view through the stoker of Fig. 1;

Fig. 5 is a similar section through a slightly modified stoker construction;

50 Fig. 6 is an elevation of a stoker section constructed in accordance with the showing of Fig. 5;

55 Figs. 7, 8 and 9 are detail sectional views illustrating modified arrangements of cooling of the under-feed section where such

cooling is restricted to the tuyères alone; and

Figs. 10, 11, 12 and 13 are similar sectional views illustrating a construction wherein the cooling includes both the tuyères and the retort walls.

60 Referring now more particularly to the drawings, the numeral 10 generally designates the under-feed section of a stoker furnace, 11 the over-feed section thereof, and 12 the adjacent crusher pit wall.

65 In accordance with my invention, water-cooled tubes are provided for cooling any or all of these sections. In Figs. 1 to 4 inclusive I have illustrated a construction where all of these sections are cooled and in which a header 13 is arranged at the front wall and a header 14 at the bottom of the crusher pit wall, these headers being connected by tubes 70 15 which extend along the under-feed section, preferably in contact with the tuyères thereof as more particularly shown in Fig. 3.

75 At the over-feed section 11 the over-feed pusher 16 is preferably increased in depth so that an increased arc in bending the tubes, as indicated at 17, may be provided. From the bend 17 these tubes extend downwardly along the front pusher pit wall and connect to the header 14. In a construction of this character any of the tuyère and retort wall cooling arrangements of Figs. 4 and 7 to 11 may be provided. Such a construction is, however, disadvantageous to a certain extent 80 in that it does not permit of cooling of the sections 12a of the crusher pit wall which are in alignment with the retort. Where cooling of these sections is desired the arrangement of Figs. 5 and 6 is employed. In 85

90 In these figures an intermediate header 18 is disposed between the headers 13 and 14 and at the top of the crusher pit wall. The tubes 15 are divided into sections 15a and 15b of which the sections 15a extend from the front wall to the header 18 and the sections 15b from the header 18 to the header 14, the first-named sections cooling the tuyères, and, if desired, the retort walls, while the last-named sections cool the crusher pit wall in alignment with the tuyères.

95 So far the construction described provides the same cooling as that provided by the construction originally described. However, header 18 may be connected with the header 14 by additional tubes 19 underlying the 100 105 110

retort section which serve to cool those portions of the crusher pit wall in alignment with the retort sections. If desired, in a construction of the latter character the cooling may be confined to the tuyères and the retort walls by omitting header 14 and pipe sections 15b and 19. Similarly the cooling may be confined to the crusher pit wall by omitting the header 13 and pipe sections 15a. 5
10 The headers 13 and 14 may be either supplied with cooling fluid from a separate source or, as illustrated, be interconnected with the circulation system of the boiler through conduits 21 and 22. This arrangement may be employed without any material modification of the stoker construction and will result in a considerable saving due to the extension of the life of the parts affected where the stoker is employed with highly 15
20 pre-heated air. It may, of course, be provided in any stoker construction.

In many instances it may prove desirable to cool the pushers 23, partition plates 24 and the over-feed section 16 of the furnace.

25 This is accomplished by making each of these sections in the form of a chamber having fluid feed and return pipes 25 and 26 communicating therewith. The feed and return pipes leading to the over-feed section 16 and 30 the pushers will, of necessity, include flexible sections since these parts are reciprocated through the usual mechanism generally designated at 27. Those leading to the partitions 24 may, however, be in the form of 35 rigid tubes.

It will be noted that the lower portion of the front wall will be cooled by fluid from header 13 and by the vertically-extending conduits 21. It will, therefore, be obvious 40 that by combining with the features hereinbefore described a side wall structure such as set forth in my prior application, Serial No. 314,098, filed October 22, 1928, for water wall and air cooled refractory construction 45 the entire fire zone may be water-cooled. The cooling structure described in said application includes headers 28 and 29 located adjacent the rear and front walls of the furnace and connected by inclined tubes 30 50 built into the side walls of the furnace, these tubes covering the entire fire zone of the furnace side wall. Circulation is established through the headers 28 and 29 and tubes 30 55 by connecting the same with the circulatory system of the boiler through conduits 31 and 32.

In Figs. 3 and 7 to 13 inclusive I have 60 illustrated various arrangements of the tubes which may be conveniently employed. In 65 the usual practice these tubes will be covered by blocks 33 which may be either of the U type as illustrated in Figs. 3 and 7 to 11 inclusive or of the T type as illustrated in Fig. 12. It will be noted, however, from an 65 inspection of Fig. 13 that it is not necessary

that these tubes be covered, as they may actually form the retort side walls and the tuyère section as suggested in this figure.

Since the structure illustrated is capable of a considerable range of change and modification without in any manner departing from the spirit of my invention, I do not wish to be understood as limiting myself thereto except as hereinafter claimed.

I claim:

1. In combination with a stoker furnace having a crusher pit, a front wall and the usual under-feed and over-feed sections extending from the front wall to the upper end of the crusher pit wall, means for fluid cooling the tuyère sections and said crusher pit wall including fluid circulation tubes extending from said front wall to the lower end of said crusher pit wall, said tubes being formed in sections, there being a header at the upper end of the crusher pit wall with which adjacent ends of the sections communicate.

2. In combination with a stoker furnace having a crusher pit, a front wall and the usual under-feed and over-feed sections extending from the front wall to the upper end of the crusher pit wall, means for fluid cooling the tuyère sections and said crusher pit wall including fluid circulation tubes extending from said front wall to the lower end of said crusher pit wall, said tubes being formed in sections, there being a header at the upper end of the crusher pit wall with which adjacent ends of the sections communicate and headers at the front wall and lower end of the crusher pit wall with which the remaining ends of the sections communicate.

3. In combination with a stoker furnace having a crusher pit, a front wall and the usual under-feed and over-feed sections extending from the front wall to the upper end of the crusher pit wall, means for fluid cooling the tuyère sections and said crusher pit wall including fluid circulation tubes extending from said front wall to the lower end of said crusher pit wall, said tubes being formed in sections, there being a header at the upper end of the crusher pit wall with which adjacent ends of the sections communicate and headers at the front wall and lower end of the crusher pit wall with which the remaining ends of the sections communicate, the last-named headers being connected in the circulation system of the boiler.

4. A stoker furnace including retort walls, said retort walls comprising fluid circulation tubes and refractory elements in heat-conductive relation with said tubes and forming the effective wall surfaces, other fluid circulation tubes extending longitudinally between the upper ends of said retort walls, tuyère elements in heat-conductive relation with said last-named tubes, and means for circulating fluid through said tubes.

5. A stoker furnace including retort walls, said retort walls comprising fluid circulation tubes, other fluid circulation tubes extending longitudinally between the upper 5 ends of said retort walls and means for circulating fluid through said tubes, protective block facing the retort walls and tuyères seated upon the last-named tubes. 70
6. In a stoker furnace, the combination 10 with an inclined grate structure consisting of alternately arranged longitudinally extending tuyères and retorts, of an ash pit terminating the lower end of the grate, fluid circulation tubes in cooling and protective relation to the tuyères and aligned portions of the wall of said pit, and other fluid circulation tubes in corresponding relation to those parts of the said wall in alignment with said 15 retorts. 75
- 20 7. A mechanical stoker comprising an inclined grate consisting of alternately arranged longitudinally extending tuyères and retorts, fuel-feeding pushers in the bottoms of said retorts, and fluid cooling means in 25 cooling and protective relation both to the tuyères and said pushers. 80
8. In a stoker furnace, a grate comprising alternated tuyères and retorts, means for advancing fuel in the retorts, an ash pit terminating said grate, and walls surrounding said grate and pit, and fluid cooling means in cooling and protective relation to said walls, tuyères, retorts, fuel advancing means, and with the walls of said pit and forming 35 a completely fluid cooled enclosure embracing the entire fire zone of said furnace. 85
9. In a mechanical stoker, a plurality of parallel tubes arranged in groups and defining a plurality of spaced retorts, protective 40 blocks secured to the tubes and forming the wall facings of said retorts, and tuyères also associated with the tubes and bridging the spaces between said retorts. 90
- 45 10. In a mechanical stoker, a plurality of parallel banks of fluid circulating tubes defining the walls of spaced retorts, protective blocks secured to the tubes and forming the wall facings of the retorts, and tuyères bridging the spaces between the retorts. 100
- 50 11. In a mechanical stoker, a plurality of parallel banks of fluid circulating tubes defining the walls of spaced retorts, protective blocks secured to the tubes and forming the 55 wall facings of the retorts, tuyères bridging the spaces between the retorts, and fluid cooled pushers operative in the bottoms of said retorts. 105
- 60 12. In an underfeed stoker furnace, the combination with a boiler, of a series of inclined tuyères forming a series of retorts, inclined longitudinally toward an ash discharge at the lower ends of the retorts, a 110 transverse water header embodied in cooling relation across the lower ends of the retorts and over which the ashes discharge, a down-take connection from the boiler feeding water to said header, uptakes extending from the header along the tuyères in cooling relation thereto, and uptake connections from said uptakes to the boiler, said tuyères being of section tapering upwardly to a ridge, with one of said water uptakes embodied in cooling relation within the ridge. 115
